UNITED STATES PATENT OFFICE

100,425

DESIGN FOR AN INSTRUMENT CASE

Lurelle Guild, Darien, Conn., assignor to Weston
Electrical Instrument Corporation, Newark,
N. J., a corporation of New Jersey

Application May 22, 1936, Serial No. 62,780

Term of patent 7 years

To all whom it may concern:

Be it known that I, Lurelle Guild, a citizen of the United States, residing at Darien, county of Fairfield, State of Connecticut, have invented a new, original, and ornamental Design for an Instrument Case, of which the following is a specification, reference being had to the accompanying drawing, forming part thereof, and wherein:

Figs. 1 and 2 are a front elevation and a side view, respectively, of the instrument case, showing my new design.

I claim:

The ornamental design for an instrument case, as shown.

LURELLE GUILD.
